UNITED STATES PATENT OFFICE.

FRANCIS F. HAMILTON, OF INDIANAPOLIS, INDIANA.

EXHAUST MUFFLER.

Application filed March 15, 1928. Serial No. 261,753.

This invention relates to a muffler of the type adapted to receive the exhaust gases from hydrocarbon engines of the type commonly employed in automobiles and the like, and has for its purpose the reduction or elimination of the back pressure created by the heretofore commonly used mufflers, at the same time permitting a noiseless escape of the gases.

10 By means of this invention, the gases travel through my muffler in a continuous direction without being reversed, the gases being first spread out to travel paths of unequal lengths into a large expansion chamber, the extent of travelling over longer distances of part of the gases being dependent entirely upon the rapidity of discharge of gases into the muffler, thence permitting the gases to flow on through the muffler to 20 be brought together again at the rear discharge end after having come through paths of unequal length.

The invention is described in one particular form in reference to the accompanying 25 drawing, in which—

Fig. 1 is a fragmentary top plan view of a muffler embodying the invention;

Fig. 2, a vertical transverse section through the muffler on the line 2—2 in 30 Fig. 1;

Fig. 3, a vertical transverse section on the line 3—3 in Fig. 1; and

Fig. 4, an outer end elevation of a cone employed in each end of the muffler.

35 Like characters of reference indicate like parts throughout the several views of the drawing.

I form a housing 5 of greater length than width to have a cross-sectional periphery substantially as indicated in Figs. 2 and 3, though the particular shape may be varied from a circle to any polygonal shape (not shown) provided a certain feature is maintained as will be indicated below.

40 In each end of the housing 5 I mount a reflector 6 by means of the spacing fingers 7 which are welded to the housing 5 and hold the reflector 6 out of contact with the housing wall to have substantially a uniform opening entirely around therebetween save for the extension of the supporting fingers 7 thereacross. Each reflector 6 presents a concave face from the inner side of the housing directed one toward the other.

55 A partition 8 is fixed between the reflectors 6, within and transversely of the housing, to the rear of the transverse center line of the housing to divide the housing into a large forward expansion chamber and a smaller rear expansion chamber. Over to 60 one extreme side of the partition, a single orifice 9 is cut therethrough to permit gases to flow from one chamber to the other.

On the outer sides of each of the reflectors 6 is secured a shell 10 formed to have 65 a sharp vertex extended from the reflector with the walls of the shell embodying straight line elements everywhere sloping outwardly from the vertex to the periphery of the reflector 6, the whole shell and reflector forming a cone-like solid which while not a true cone, will hereinafter be termed a cone.

70 The vertex of each cone however is not central of the base or reflector 6, but lies on the longitudinal center line through the orifice 9.

A head 11 is secured to each end of the housing 5 to surround the protruding cones to define a continuous space entirely around 80 and therebetween. The forward head 11 receives the exhaust pipe 12 centrally of the vertex of the cone and a plurality of posts 13, here shown as three in number are welded in place between the head 11 and the vertex 85 end of the shell 10. Similarly the rear head 11 carries a discharge or tail pipe 14 with its center line coinciding with the center line of the cone vertices.

Gases discharging from the exhaust pipe 90 12 strike the vertex of the cone and are distributed or differentiated to travel between the head 11 and the shell 10 toward the large expansion chamber. Obviously, as the vertex of the cone is not central of the reflector 95 6, some of the gases travel a greater distance "a" from the end of the pipe 12 to the chamber than do gases going the shorter way "b", Fig. 1, so that for a given discharge from the pipe 12, there is a time interval 100 before all of the discharge arrives in the expansion chamber.

The hole 9 permits the gases to move from the larger expansion chamber into the rear chamber, and from there the gases pass 105 around the edges of the rear reflector 6 between the shell 10 and the head 11 where again the gases may travel varying distances before the tail pipe 14 is reached to permit escape of the gases into the atmosphere.

The centers of curvature of the reflectors 6 are within the respective front and rear expansion chambers.

As above indicated, the exact cross-sectional shape of the housing is immaterial. It is essential that the center line of the muffler intake, the partition hole 9 and the muffler outlet be decidedly to one side of the longitudinal center line of the muffler expansion chambers.

15 While I have herein described my invention in the form now best known to me, it is obvious that structural variations may be introduced without departing from the spirit of the invention, and I, therefore, do not desire to be limited to the precise structure as shown and described, nor any more than may be necessitated by the following claims.

I claim:

- 20 1. In a muffler of exhaust gases, a housing, a forward head on the housing, said head having an intake opening to one side of the central portion of the head, a deflector having its vertex just back of said opening, a
25 partition extended transversely across the housing to divide the housing into a forward and a rearward chamber, said partition having an opening therethrough offset considerably from the center, a rear head on
30 the housing having a discharge opening therefrom, and a deflector having its vertex just ahead of the discharge opening, said discharge opening being considerably to one side of the central longitudinal axis of the
35 housing.

2. A muffler housing having an end enclosed by a head projecting outwardly therefrom and drawn in to a vertex considerably to one side of the central axis of the housing,
40 and a body similar in shape to and mounted in the end of the housing to have its vertex pointed toward but spaced back of said head vertex whereby there is a space entirely around the body between it and the projected head, said housing having its opposite end projected outwardly therefrom and drawn to a vertex considerably to one side of the axial center of the housing, a body similar in shape to and carried in the said
45 opposite drawn end to have its vertex spaced just back of the end vertex whereby the body
50

defines a space around and between it and the housing end communicating to within the housing, and a transverse partition in said housing defining two chambers therein, said partition having an opening therethrough. 55

3. A muffler housing having an end enclosed by a head projecting outwardly therefrom and drawn in to a vertex considerably to one side of the central axis of the housing, and a body similar in shape to and mounted in the end of the housing to have its vertex pointed toward but spaced back of said head vertex whereby there is a space entirely around the body between it and the projected head, said housing having its opposite end projected outwardly therefrom and drawn to a vertex considerably to one side of the axial center of the housing, a body similar in shape to and carried in the said opposite drawn end to have its vertex spaced just back of the end vertex whereby the body defines a space around and between it and the housing end communicating to within the housing, each of said two bodies having a concave face presented to within the housing.

4. A muffler housing having an end enclosed by a head projecting outwardly therefrom and drawn in to a vertex considerably so to one side of the central axis of the housing, and a body similar in shape to and mounted in the end of the housing to have its vertex pointed toward but spaced back of said head vertex whereby there is a space 85 entirely around the body between it and the projected head, said housing having its opposite end projected outwardly therefrom and drawn to a vertex considerably to one side of the axial center of the housing, a 90 body similar in shape to and carried in the said opposite drawn end to have its vertex spaced just back of the end vertex whereby the body defines a space around and between it and the housing end communicating to 95 within the housing, each of said two bodies having a concave face presented to within the housing, and a partition across said housing between said concave faces having an opening therethrough. 100

In testimony whereof I affix my signature,

FRANCIS F. HAMILTON
